CLAIM

The ornamental design for a combined pen and magnetic holder therefor, as shown and described.

DESCRIPTION

FIG. 1 is a left front perspective view of a combined pen and magnetic holder therefor showing my new design;

FIG. 2 is a front elevational view;

FIG. 3 is a rear elevational view;

FIG. 4 is a left side elevational view;

FIG. 5 is a right side elevational view;

FIG. 6 is a top plan view; and

FIG. 7 is a bottom plan view thereof.
